(57) **CLAIM**

The ornamental design for a set of comb heads as shown and described.

DESCRIPTION

FIG. 1 is a front, right and top perspective view of a set of comb heads showing my design.

FIG. 2 is a front, right and top perspective view of the Accessory 1 of the set of comb heads.

FIG. 3 is a rear, left and bottom perspective view of the Accessory 1 of the set of comb heads in FIG. 2.

FIG. 4 is a front elevation view of the Accessory 1 of FIG. 2.

FIG. 5 is a rear elevation view of the Accessory 1 of FIG. 2.

FIG. 6 is a left side elevation view of the Accessory 1 of FIG. 2.

FIG. 7 is a right side elevation view of the Accessory 1 of FIG. 2.

FIG. 8 is a top plan view of the Accessory 1 of FIG. 2.

FIG. 9 is a bottom plan view of the Accessory 1 of FIG. 2.

FIG. 10 is an enlarged view of detail 10 in FIG. 2.

FIG. 11 is an enlarged view of detail 11 in FIG. 3.

FIG. 12 is another front, right and top perspective view “of the Accessory 1” of the set of comb heads in a usable state.

FIG. 13 is a front, right and top perspective view of the Accessory 2 of the set of comb heads.

FIG. 14 is a rear, left and bottom perspective view of the Accessory 2 of the set of comb heads in FIG. 13.

FIG. 15 is a front elevation view of the Accessory 2 of FIG. 13.

FIG. 16 is a rear elevation view of the Accessory 2 of FIG. 13.

FIG. 17 is a left side elevation view of the Accessory 2 of FIG. 13.

FIG. 18 is a right side elevation view of the Accessory 2 of FIG. 13.

FIG. 19 is a top plan view of the Accessory 2 of FIG. 13.

FIG. 20 is a bottom plan view of the Accessory 2 of FIG. 13.

FIG. 21 is another front, right and top perspective view “of the Accessory 2” of the set of comb heads in a usable state.

FIG. 22 is a front, right and top perspective view of the Accessory 3 of the set of comb heads.

(Continued)

FIG. 23 is a rear, left and bottom perspective view of the Accessory 3 of the set of comb heads in FIG. 22.

FIG. 24 is a front elevation view of the Accessory 3 of FIG. 22.

FIG. 25 is a rear elevation view of the Accessory 3 of FIG. 22.

FIG. 26 is a left side elevation view of the Accessory 3 of FIG. 22.

FIG. 27 is a right side elevation view of the Accessory 3 of FIG. 22.

FIG. 28 is a top plan view of the Accessory 3 of FIG. 22.

FIG. 29 is a bottom plan view of the Accessory 3 of FIG. 22.

FIG. 30 is another front, right and top perspective view “of the Accessory 3” of the set of comb heads in a usable state.

FIG. 31 is a front, right and top perspective view of the Accessory 4 of the set of comb heads.

FIG. 32 is a front, left and bottom perspective view of the Accessory 4 of the set of comb heads in FIG. 31.

FIG. 33 is a front elevation view of the Accessory 4 of FIG. 31.

FIG. 34 is a rear elevation view of the Accessory 4 of FIG. 31.

FIG. 35 is a left side elevation view of the Accessory 4 of FIG. 31.

FIG. 36 is a right side elevation view of the Accessory 4 of FIG. 31.

FIG. 37 is a top plan view of the Accessory 4 of FIG. 31.

FIG. 38 is a bottom plan view of the Accessory 4 of FIG. 31.

FIG. 39 is another front, left and top perspective view “of the Accessory 4” of the set of comb heads in a usable state.

FIG. 40 is an enlarged view of detail 40 in FIG. 31.

FIG. 41 is an enlarged view of detail 41 in FIG. 31.

FIG. 42 is an enlarged view of detail 42 in FIG. 32.

FIG. 43 is a front, right and top perspective view of the Accessory 5 of the set of comb heads.

FIG. 44 is a rear, left and bottom perspective view of the Accessory 5 of the set of comb heads in FIG. 43.

FIG. 45 is a front elevation view of the Accessory 5 of FIG. 43.

FIG. 46 is a rear elevation view of the Accessory 5 of FIG. 43.

FIG. 47 is a left side elevation view of the Accessory 5 of FIG. 43.

FIG. 48 is a right side elevation view of the Accessory 5 of FIG. 43.

FIG. 49 is a top plan view of the Accessory 5 of FIG. 43.

FIG. 50 is a bottom plan view of the Accessory 5 of FIG. 43.

FIG. 51 is another front, right and top perspective view “of the Accessory 5” of the set of comb heads in a usable state.

FIG. 52 is a front, right and top perspective view of the Accessory 6 of the set of comb heads.

FIG. 53 is a rear, left and bottom perspective view of the Accessory 6 of the set of comb heads in FIG. 52.

FIG. 54 is a front elevation view of the Accessory 6 of FIG. 52.

FIG. 55 is a rear elevation view of the Accessory 6 of FIG. 52.

FIG. 56 is a left side elevation view of the Accessory 6 of FIG. 52.

FIG. 57 is a right side elevation view of the Accessory 6 of FIG. 52.

FIG. 58 is a top plan view of the Accessory 6 of FIG. 52.

FIG. 59 is a bottom plan view of the Accessory 6 of FIG. 52.

FIG. 60 is another front, right and top perspective view “of the Accessory 6” of the set of comb heads in a usable state.

FIG. 61 is an enlarged view of detail 61 in FIG. 52; and, FIG. 62 is an enlarged view of detail 62 in FIG. 53.

The dashed broken lines depict portions of the set of comb heads that form no part of the claimed design.

The dot-dash broken lines in FIGS. 2, 3, 10, 11, 31, 32, 40, 41, 42, 52, 53, 61, 62 depict the boundaries of the enlargements that form no part of the claimed design.

1 Claim, 62 Drawing Sheets
